UNITED STATES PATENT OFFICE

FRANKLIN B. HUNT, OF OAK PARK, ILLINOIS, ASSIGNOR TO THE LIQUID CARBONIC CORPORATION, OF CHICAGO, ILLINOIS, A CORPORATION OF DELAWARE

REFRIGERATING SYSTEM

Application filed January 21, 1927. Serial No. 162,601.

REISSUED

My invention relates to improvements in refrigerating systems, and it consists in the combinations, constructions, and arrangements herein described and claimed.

5 An object of my invention is to provide a refrigerating system for cooling syrup cans in soda fountains, and in which the cooling mechanism takes up a minimum space.

10 A further object is to provide a device of the type described in which the cooling of the cans is accomplished with the addition of comparatively little cooling apparatus, and in which use is made of the so-called boilers which are ordinarily used.

15 A further object of my invention is to provide a device of the type described wherein the refrigerant liquid may be moved through a by-pass which is positioned above the common liquid level.

20 A further object of my invention is to provide a device of the type described by means of which the high pressure in one refrigerant liquid container is utilized for forcing the liquid through an additional cooling line to the other refrigerant liquid container.

25 Other objects and advantages will appear in the following specification, and the novel features of the invention will be particularly pointed out in the appended claims.

30 My invention is illustrated in the accompanying drawings, forming part of this application, in which

Figure 1 is a sectional view of a soda fountain with my device applied thereto,

35 Figure 2 is an enlarged section substantially along the line 2—2 of Figure 1, and

Figure 3 is a modified form of my device.

40 In carrying out my invention, I make use of a soda fountain 1 having aligned compartments 2 and 3 and a syrup enclosure 4 which is positioned above the compartments 2 and 3.

45 A high pressure boiler 5 is disposed in the compartment 2 and provided with a header 6 and a plurality of tubes or coils 7 having their ends in communication with the header 6. A low pressure boiler 8 is disposed in the compartment 3 and provided with a header 9 having tubes or coils 10 communicating therewith.

A compressor 11 is provided with a motor 12 and communicates with a condenser 13 through a tube 14. A liquid line 15 passes from the lower portion of the condenser 13 to the lower portion of the header 6. A float 55 valve 16 is pivotally mounted at 17 within the header 6. The float valve 16 is provided with a plunger 18 which is adapted to close the opening of the liquid line 15 for governing the flow of liquid within the header 6. 60 A gas line 19 extends from the upper portion of the header 6 to the upper portion of the header 9 and is provided with an automatic adjusting valve 20. The purpose of the valve 20 is to maintain a predetermined pressure in the header 6 and by so doing the compressor is only allowed to draw gas from the header 6 until this predetermined pressure is reached. A gas line 21 communicates with the gas line 19 at 22 and extends to the compressor 11. A cooling line 23 extends from the lower portion of the header 6 into and through the syrup enclosure 4 and into the compartment 3 where it communicates with the lower portion of the header 9. A float valve 24 which is identical in construction to the float valve 16 is disposed in the header 9 and is adapted to govern the flow of liquid into the header 9. A refrigerant liquid 25, such as sulphur dioxide, is disposed within the boilers 5 and 8.

70 In Figure 2, I have shown an enlarged sectional view through the syrup enclosure 4. It is clearly shown in this view how the cooling line 23 extends beneath syrup containers 26 which are disposed within the syrup enclosure 4.

75 From the foregoing description of the various parts of the device, the operation thereof may be readily understood. Let us assume that the compressor 11 is provided with the usual automatic switch for starting and stopping the compressor at predetermined periods. Let us also assume that the compressor has been stopped for a time sufficient to allow the compartments 2 and 3 and the syrup enclosure 4 to get relatively warm. The heat within the compartment 2 will be taken in through the tubes 7 and into the refrigerant liquid 25. As the refrigerant liq-

uid boils at a very low temperature, the heat taken in through the coils or tubes 7 will cause the liquid to boil and form a gas. When a predetermined amount of pressure has been developed within the headers 6 and 9, the compressor 11 will automatically start operating. Operation of the compressor will force liquid into the header 6 for maintaining as nearly as possible a predetermined level within the header 6. The compressor will also draw the gases from the header 9 into the compressor where the gases are compressed and forced into the condenser 13 where they are again changed into liquid form. The valve 20 prevents the compressor from drawing gas from the header 6, after the gas within the header 6 has reached a predetermined point. Therefore, the pressure in the header 6 is greater than the pressure in the header 9.

The difference between the pressure in the header 6 and the pressure in the header 9 is sufficient to cause liquid to flow from the header 6 through the cooling line and into the header 9. As the liquid flows through the cooling line 23, heat within the syrup enclosure is picked up by the liquid. The heat which is received by the liquid causes the liquid to boil, thus forming gas. This operation is continued until the heat within the syrup enclosure has been eliminated by the liquid, thus making the enclosure the desired temperature.

The compressor 11 continues in its operation until the heat within the compartment 2 has been eliminated by the liquid within the boiler 5, until the heat within the syrup enclosure 4 has been eliminated by the liquid passing through the cooling line 23, and until the heat within the compartment 3 has been eliminated by the liquid within the boiler 8. When this has been accomplished, the gas which has been formed by the receiving of the heat has again been transformed into a liquid, thus reducing the pressure within the headers and permitting the compressor to stop actuating.

In Figure 3, I have shown a modified form wherein the cooling line 23 is provided with an expansion valve 27 and is in communication with the liquid line 15 instead of the header 6, as shown in Figure 1. The boiler 5 and the valve 20 are not essential in causing the liquid to flow through the cooling line 23. By setting the expansion valve to maintain a higher pressure in the cooling line 23 than the pressure at which the boiler 8 is operating, liquid will flow through the cooling line whenever the float valve 24 is open.

Although I have shown my refrigerating system applied to a soda fountain, it is obvious that the system may be applied to numerous other devices, which contain articles

to be cooled, such as display cases, ice boxes, and the like.

I claim:

1. In combination with compartments, of evaporators positioned within said compartments, means for supplying liquid refrigerant to said evaporators in series comprising a compressor and condenser, a liquid supply line connecting said condenser and the first of said evaporators, a second liquid supply line connecting said first evaporator and the second evaporator, communicating therewith below the liquid level therein, and means for conducting vaporized refrigerant from said evaporators to said compressor comprising a common return conduit and branch conduits connecting said evaporators with said common return conduit. 70

2. In combination with aligned compartments of evaporators positioned within said compartments, means for supplying liquid refrigerant to said evaporators in series comprising a compressor and condenser, a liquid supply line connecting said condenser and the first of said evaporators, a second liquid supply line connecting said first evaporator and the second evaporator, communicating therewith below the liquid level therein, means for conducting vaporized refrigerant from said evaporators to said compressor comprising a common return conduit and branch conduits connecting said evaporators with said common return conduit, and a pressure responsive valve in the branch conduit connecting said first evaporator whereby said evaporators 85 may be maintained at different temperatures. 90

3. In combination with aligned compartments and an enclosure positioned above said compartments, of evaporators positioned within said compartments, means for supplying liquid refrigerant to said evaporators in series comprising a compressor and condenser, a liquid supply line connecting said condenser and the first of said evaporators, a second liquid supply line connecting said first evaporator and the second evaporator, communicating therewith below the liquid level therein and passing through said enclosure, means for conducting vaporized refrigerant from said evaporator to said compressor comprising a common return conduit and branch conduits connecting said evaporators with said common return conduit, and a pressure responsive valve in the branch conduit connecting said first evaporator whereby said evaporators may be maintained at different temperatures. 105

FRANKLIN B. HUNT.
